UNITED STATES PATENT OFFICE.

WILLIAM J. HUCKETT, OF MARSHALL, MICHIGAN.

IMPROVEMENT IN SWINGS.

Specification forming part of Letters Patent No. 36,216, dated August 19, 1862.

To all whom it may concern:

Be it known that I, WILLIAM J. HUCKETT, of the city of Marshall, in the county of Calhoun and State of Michigan, have invented a new and useful Improvement in Swings; and I do hereby declare that the following is a full, clear, and exact description of the construction and operation of the same, reference being had to the annexed drawing, making a part of this specification, which gives a perspective representation of the swing in full operation.

The object of this improvement is to furnish children, invalids, or others who are fond of swinging with an easy mode of starting a swing and preserving and regulating its vibrations without assistance from any one, the exertion necessary being no more than sufficient to constitute a healthful exercise; and the better to enable others to construct and use my invention I will now proceed to describe it.

A A represent two stout wooden posts let deep in the ground and sufficiently high to give the required arc of vibration, and B is a wooden girt framed in between the said posts near the top.

A car, C, fitted with one or more seats, is suspended by two iron or wooden hanging bars, D D, fastened to the sides of the car by means of hooks *aa*, attached to the upper ends, fitted to eyebolts passing through the said girt B, or by a rod passing through the posts and hanging bars, or in any other more cheap or convenient manner not involving great friction.

When it is desired to accomplish, in connection with the swinging action, some useful mechanical effect—such as working a pump, &c.—I then attach the hanging bars D D rigidly to a rocking shaft (not shown) with bearings in the posts and having one overhanging end, to which an arm (not seen) is fitted for

communicating a reciprocating motion by the vibration of the car.

P' and P² are two pulley-blocks, one of which, P', is connected by a loop to the center of an iron or wooden cross bar, E, which is framed into or otherwise attached to the hanging bars D D at a proper distance below the points of suspension, the other pulley, P², being fastened to the center of a hanging bow, H, projecting beyond the posts, to the sides of which it is secured, and which I usually strengthen by a brace-bar, I, attached to it and the girt B. A cord, X, is attached to the eye of the pulley-block P' and passes to pulley P², and from thence to and over pulley P' downward to the hands of the swinger in the car G.

The mode of operation is as follows: The operator, seated in the car, as it hangs vertically in a state of rest, grasps the cord by its tassel and pulls it in a downward direction, which causes the car to make a partial vibration, by reason of the connection of the other end of the cord to pulley-block P', attached to the cross-bar E of the swinging frame, when the cord is slackened to allow the return vibration and then tightened and loosened alternately, in the manner of ringing a large bell, until full vibrations are obtained, which can be continued for any desired length of time with but little effort.

What I claim as my invention, and desire to secure by Letters Patent, is—

The application and use of the pulley-blocks P' P² and connecting-cord X, when arranged and connected relatively with each other and with the frame and swing, in the manner as and for the purposes specified.

W. J. HUCKETT.
